UNITED STATES PATENT OFFICE.

ERNEST A. HERZBERG AND GEORGE H. HERZBERG, OF SEATTLE, WASHINGTON.

FLOOR STRUCTURE.

1,085,862.

Specification of Letters Patent.

Patented Feb. 3, 1914.

Application filed November 25, 1912. Serial No. 733,306.

To all whom it may concern:

Be it known that we, ERNEST A. HERZBERG and GEORGE H. HERZBERG, citizens of the United States, residing at Seattle, in the 5 county of King and State of Washington, have invented certain new and useful Improvements in Floor Structures, of which the following is a specification.

This invention relates to fire-proof floor 10 and ceiling construction; and its object is the adaptation and utilization of the so-called "plaster-boards" or an equivalent, wherefrom a tubular frame is constructed to be embedded in cement, concrete or other 15 material which is employed in the floor structure.

The invention consists in the novel construction and combination of parts, as will be hereinafter described and claimed.

20 In the accompanying drawings, Figure 1 is a transverse sectional view of a portion of a floor, constructed in accordance with the present invention. Fig. 2 is a perspective view of a tubular form-member such as 25 illustrated in Fig. 1. Fig. 3 is a perspective view of an element of the form-member. Fig. 4 is a fragmentary transverse sectional view of the preferred form of plaster-board for use in manufacturing the form-member 30 elements.

In carrying out our invention, we employ a plurality of form-members of substantially rectangular shapes in cross section. Each of these form-members, as best 35 shown in Fig. 2, consists of a U-shaped lower element comprising a bottom part 5 and side walls 6 extending upwardly from the lateral edges thereof; and an inverted U-shaped upper element comprising a top part 40 7 and side walls 7¹ depending therefrom. The side walls 7¹ of the upper element are disposed to be introduced between the side walls of the lower element and are coupled together by fastenings, such as nutted bolts 45 8 passing through apertures 9 and 9¹ provided in the respective side walls. The apertures 9¹ of an upper element are elongated to enable the elements of a member to be secured to afford a depth suitable to 50 the floor for which intended. These elements of a form-member are constructed of plates, conventionally known as "plasterboards", and is desirably comprised of a 55 layer of a plastic material *a*, Fig. 4, interposed between two sheets *b* of paper, al-

though other types of plaster board may be substituted. In the manufacture of the aforesaid elements of a form-member, the boards are first made on a table in the usual manner and then are bent or molded into U- 60 shape and are thus allowed to harden or become "set".

In the construction of a floor, the form-members disposed in rows are placed in predetermined spaced positions upon a temporary platform, or falsework, designated by 11 in Fig. 1. The reinforcing bars 12 supported by stirrups 13 are inserted in the spaces between the rows of said members. Cement or concrete, indicated by 14, is then 70 filled in between the rows of the members and to a distance above the tops of the latter to the height of the floor 15, and to embed a metal web 16 such as "wire lath." The cement or concrete 14 will adhere to the exteriors of the form-members to form a substantially homogeneous body therewith. After the structure thus far completed becomes firm, the platform 11 is removed and the ceiling plaster 17 is applied directly to 80 the form-members and to the exposed bodies of concrete intermediate the members. 75

The advantages of this invention reside principally in the use of forms of minimum weight and a maximum amount of adhesive 85 properties with respect to the floor concrete material and ceiling plaster.

Walls or floors constructed with these devices are deemed thoroughly fire-proof by the underwriters and are recommended for 90 use in modern buildings where the floor spaces are relatively small.

What we claim is—

A form-member for floor construction or the like, consisting of two opposing U- 95 shaped elements, the side walls of one element provided with spaced elongated openings, the side walls of the other element provided with spaced apertures registering with said openings, and clamping means extending through said openings for securing the elements together. 100

Signed at Seattle, Wash., this 8th day of November, 1912.

ERNEST A. HERZBERG.
GEORGE H. HERZBERG
